Jens J. Moll and William C. Chapman,
Chicago, Ill.

Application March 16, 1935, Serial No. 55,906

Term of patent 7 years

To all whom it may concern:

Be it known that we, Jens J. Moll and William C. Chapman, citizens of the United States and residents of Chicago, in the county of Cook and State of Illinois, have invented a new, original, and ornamental Design for a Rug, of which the following is a specification, reference being had to the accompanying drawing, forming a part thereof.

The drawing is a plan view of approximately a $\frac{1}{4}$ section of a rug showing our new design, the other three sections being of the same design arranged in proper relation to complete the rug.

The rug is composed of material having contrasting and different colors forming a border and edge of a block design in which the principal colors are alternated. The rug may be more particularly described as composed of chenille.

We claim:

The ornamental design for a rug, as shown and described.

JENS J. MOLL,
WILLIAM C. CHAPMAN.
